ILLUMINATED CARD HOLDER

Leo John Buhr, Lake Zurich, Ill.

Application June 14, 1933. Serial No. 675,861

1 Claim. (Cl. 40—132)

The present invention relates to an illuminated card holder for use particularly on automobiles for displaying in a prominent manner identification cards, and has for one of its important objects to provide, in a manner as hereinafter set forth, a device of this character embodying a novel construction, combination and arrangement of parts through the medium of which the cards may be locked in position against unauthorized removal.

Other objects of the invention are to provide an illuminated card holder of the aforementioned character which will be simple in construction, strong, durable, attractive in appearance, reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an illuminated card holder constructed in accordance with the present invention.

Figure 2 is a top plan view thereof.

Figure 3 is a view in side elevation of the card holder.

Figure 4 is a view in horizontal section, taken substantially on the line 4—4 of Figure 3.

Figure 5 is a perspective view of a portion of one of the channel guides.

Referring now to the drawings in detail, it will be seen that the embodiment of the invention which has been illustrated comprises a casing 1 of suitable shape, dimensions and material, said casing being open at its front and having mounted therein a reflector 2. The forward end of the reflector 2 is spaced inwardly from the open front of the casing 1, as illustrated to advantage in Figure 4 of the drawings. Mounted in the reflector 2 is a socket 3 which receives an incandescent lamp 4. Projecting laterally from the sides of the casing 1, at the forward end of said casing, are apertured ears 5 constituting means for securing the invention in position on the windshield or on a window of the automobile.

Mounted vertically in the forward portion of the casing 1 immediately adjacent the forward end of the reflector 2 are channel guides 6 which slidably receive a removable lens 7 and a transparent indicia bearing card or plate 8. The guides 6 are secured in position in the casing 1 through the medium of nut equipped bolts 9 or

other suitable means. Certain of the bolts 9 also constitute means for securing the ears 5 to the casing 1.

The forward edge of the top of the casing 1 is spaced inwardly or rearwardly from the corresponding edges of the side walls and bottom of said casing for providing an opening to permit the insertion and removal of the elements 7 and 8. Unauthorized removal of the elements 7 and 8 is prevented through the medium of a closure 10 in the form of a flat metallic bar which is hingedly secured, as at 11, on one side of the casing 1. A suitable lock 12 is provided at the free end of the closure 10 for securing said closure in closed or operative position.

As will be apparent, when the lamp 4 is illuminated, the indicia on the identification card or plate 8 will be plainly visible through the lens 7. To remove or insert the identification card or plate, it is only necessary to unlock the closure 10 and swing said closure upwardly to inoperative position, as will be obvious.

It is believed that the many advantages of an illuminated identification card holder constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

In an illuminated card holder of the character described, a casing, said casing including a back, side walls, a top wall and a bottom wall, the casing being open at its front, and having the forward edge of the top wall spaced inwardly from the corresponding edges of the side and bottom walls for providing an opening, a reflector in said casing having its forward end spaced inwardly from the front of said casing, channel guides removably disposed in the casing on the side walls and abutting the outer edge of the reflector for retaining the same in said casing, and a removable lens slidably mounted in said guides and a transparent identification card removably mounted in the guides inwardly of the lens, and a closure for the opening hingedly secured at one end to one side of the casing.

LEO JOHN BUHR.
